(57) **CLAIM**

The ornamental design for a bathroom fixture set as shown and described.

DESCRIPTION

FIG. 1 is a perspective view of the first bathroom fixture of the bathroom fixture set of FIG. 45, shown isolated from the set for clarity;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the isolated fixture of FIG. 1, shown with environmental towel hooks;

FIG. 10 is a perspective view of the isolated fixture of FIG. 1, shown with an environmental towel bar and environmental second similar fixture;

FIG. 11 is a perspective view of the isolated fixture of FIG. 1, shown with an environmental toilet paper holder;

FIG. 12 is a perspective view of the isolated fixture of FIG. 1, shown with an environmental towel ring;

FIG. 13 is a perspective view of the second bathroom fixture of the bathroom fixture set of FIG. 45, shown isolated from the set for clarity;

FIG. 14 is another perspective view thereof;

FIG. 15 is a front elevational view thereof;

FIG. 16 is a rear elevational view thereof;

FIG. 17 is a left side elevational view thereof;

FIG. 18 is a right side elevational view thereof;

FIG. 19 is a top plan view thereof;

FIG. 20 is a bottom plan view thereof;

FIG. 21 is a perspective view of the third bathroom fixture of the bathroom fixture set of FIG. 45, shown isolated from the set for clarity;

(Continued)

FIG. 22 is another perspective view thereof;
 FIG. 23 is a front elevational view thereof;
 FIG. 24 is a rear elevational view thereof;
 FIG. 25 is a left side elevational view thereof;
 FIG. 26 is a right side elevational view thereof;
 FIG. 27 is a top plan view thereof;
 FIG. 28 is a bottom plan view thereof;
 FIG. 29 is a perspective view of the fourth bathroom fixture of the bathroom fixture set of FIG. 45, shown isolated from the set for clarity;
 FIG. 30 is another perspective view thereof;
 FIG. 31 is a front elevational view thereof;
 FIG. 32 is a rear elevational view thereof;
 FIG. 33 is a left side elevational view thereof;
 FIG. 34 is a right side elevational view thereof;
 FIG. 35 is a top plan view thereof;
 FIG. 36 is a bottom plan view thereof;
 FIG. 37 is a perspective view of the fifth bathroom fixture of the bathroom fixture set of FIG. 45, shown isolated from the set for clarity;
 FIG. 38 is another perspective view thereof;
 FIG. 39 is a front elevational view thereof;
 FIG. 40 is a rear elevational view thereof;
 FIG. 41 is a left side elevational view thereof;
 FIG. 42 is a right side elevational view thereof;
 FIG. 43 is a top plan view thereof;
 FIG. 44 is a bottom plan view thereof;
 FIG. 45 is a perspective view of a bathroom fixture set, showing my new design; and,
 FIG. 46 is another perspective view of the bathroom fixture set of FIG. 45, showing my new design in an alternate position for use.
 The broken lines immediately adjacent to the shaded areas depict the bounds of the claimed design, which extends to the broken lines but does not include the broken lines; while

all other broken lines are directed to unclaimed environment. All broken lines form no part of the claimed design.

1 Claim, 46 Drawing Sheets
